F. C. ANDERSON,
DOUBLE AUTOMATIC LATCH FOR SWITCH STANDS,
APPLICATION FILED NOV. 15, 1919.

1,396,946.

FIG. 1

Patented Nov. 15, 1921.

INVENTOR
Frank C. Anderson
By James N. Ramsey
ATTORNEY

UNITED STATES PATENT OFFICE.

FRANK C. ANDERSON, OF CINCINNATI, OHIO, ASSIGNOR TO THE AMERICAN VALVE & METER COMPANY, OF CINCINNATI, OHIO, A CORPORATION OF OHIO.

DOUBLE AUTOMATIC LATCH FOR SWITCH-STANDS.

1,396,946.

Specification of Letters Patent.

Patented Nov. 15, 1921.

Application filed November 15, 1919. Serial No. 338,338.

To all whom it may concern:

Be it known that I, FRANK C. ANDERSON, a citizen of the United States, and a resident of Cincinnati, in the county of Hamilton and State of Ohio, have invented certain new and useful Improvements in Double Automatic Latches for Switch-Stands, of which the following is a specification.

My invention relates to double automatic latches such as set forth in my Patent No. 815,136, granted March 13, 1906, in which the switch levers are secured against movement under traffic and so constructed as to permit the switch-operating mechanism to operate automatically under force caused by the train running through the switch without any damage to the operating mechanism.

The object of my present invention is to simplify and improve the construction whereby the latch or keeper and coöperating mechanism may be adapted to switch-stands of varying heights or positions of the switch-stand lever without alteration of the operative elements of the switch-stands, and to keep the spring actuated plunger in an elevated position where its operation will not be interfered with by ice or other impediments. Other objects and advantages are attained as will be apparent from an examination of the device illustrated.

My invention consists in the parts and in the combination and arrangement of parts as herein set forth.

In the drawings:

Fig. 1 is a perspective view of a switch and switch-stand having my improved double automatic latch in operative connection therewith;

Fig. 2 is an elevational view of my improved double automatic latch in locked position with relation to a switch-stand lever, which is shown in transverse section, parts of the view being shown broken away and in section;

Fig. 3 is a view similar to Fig. 2, but showing the latch in lever releasing position;

Fig. 4 is a view similar to Fig. 2, but showing the latch lever removed; and

Fig. 5 is a perspective view of the latch lever.

My improved construction is provided with a latch-stand 6 having a slot 7 formed therein for the reception of switch-throwing lever 8 which is adapted to rest upon support 9 in the bottom of said slot. A bear-

ing 10 is located on a plane below the support 9 for the pivotal mounting of keeper 11 upon pivot pin 12 mounted in said bearing. The keeper 11 is provided with a finger 13 which extends through the stand 6 to a position beneath cylinder 14 located on the opposite side of stand 6 from bearing 10. This cylinder is on the opposite side of the stand from that shown in my said patented construction and in elevated position.

Within cylinder 14 a plunger 15 is located, the end thereof bearing upon finger 13 of the keeper. Upon this plunger and within cylinder 14 a coil spring is located and is held under tension by cap 17 screwed within the top of the cylinder. The pressure of plunger 15 upon the finger 13 of the keeper holds stops 21 and 22 of the upwardly extended keeper 18 against edge 19 of the latch stand, thereby maintaining nose 20 of keeper 18 in extended position over the switch-stand lever 8 when it is in latched position. The upper edge of nose 20 is beveled to permit switch-throwing lever 8 to be forced into slot 7, thus causing the keeper to tilt back against pressure of spring 16 as shown in Fig. 3. In this figure I have indicated a foot in dotted lines to show that the keeper may be tilted by foot pressure if desired.

At the upper portion of the latch-stand I have provided ears 24 having holes through which a pin or the hasp of a padlock may be passed should it be desired to prevent the switch being thrown. At the base of the latch-stand I have formed feet 25 with slots therein for the reception of spikes to hold the stands upon the cross ties as shown in Fig. 1. It will be seen upon reference to Fig. 1 that I have provided two latch stands which will take care of the switch-stand lever when thrown into either of its positions.

In my improved double automatic latch the location of the spring cylinder 14 in elevated position upon the opposite side of the latch stand from that shown in my said patent permits of increase or decrease being made in the height of support 9 from the tie upon which the latch stand is located, for the purpose of accommodating the latch or keeper to the location of any switch lever to which the latch is to be applied. This feature renders it unnecessary to alter the length of cylinder 14 in any way to accom-

modate the latch to switch levers located a short distance from the tie such as would have to be done in my patented construction. Accommodation to switch levers located a 5 greater or less distance from the surface of the tie would necessitate the mere lengthening or shortening of the switch-stand supports beneath support 9 and bearing 10, by keeping on hand castings of the required 10 length.

My invention provides the necessary means for securing the switch stand lever of switch-operating mechanism either automatically or rigidly as desired.

15 I claim:

1. A double automatic latch comprising a stand having a slot therein adapted to receive a switch stand lever and also a slot adapted to receive a keeper for said switch 20 stand lever, a spring pressed plunger mounted in elevated position on one side of the switch stand lever slot and a keeper for said switch stand lever on the opposite side of the switch stand lever slot from said 25 plunger and having a finger thereon extending through a slot therefor and adapted to engage the lower end of said spring pressed plunger whereby said keeper is adapted to be automatically opened and closed when 30 said switch stand lever is moved past said keeper in either direction.

2. A double automatic latch comprising a stand having a slot therein adapted to receive a switch stand lever, a keeper pivot- 35 ally mounted on one side of said slot and

having a nose adapted to normally project into said slot and over said switch stand lever and having a finger adapted to project beneath said slot and to the side thereof opposite said keeper and a spring pressed 40 plunger mounted in elevated position on the opposite side of said slot from said keeper and adapted to engage said finger whereby the force of said lever in operation in either direction is adapted to automatically open said keeper and whereby said keeper is adapted to automatically return to closed position before or after said lever has passed the nose thereof.

3. A double automatic latch comprising a 50 stand having a slot for a switch stand lever, and having a slot for receiving a keeper to engage said switch stand lever, a spring pressed plunger mounted in elevated position, said keeper being pivotally mounted 55 in the slot for said keeper at one side of and below said slot for said switch stand lever and having a nose normally projecting into the slot for the switch stand lever and also having a finger extending through a slot 60 therefor adapted to engage said spring pressed plunger whereby said keeper is adapted to be automatically thrown to open and closed position, respectively, when said switch stand lever is moved upwardly or 65 downwardly past said nose.

FRANK C. ANDERSON.
